UNITED STATES PATENT OFFICE.

JOSEPH M. DUCLOS, OF NEW YORK, N. Y.

IMPROVEMENT IN IRON STRUCTURES.

Specification forming part of Letters Patent No. **132,260**, dated October 15, 1872.

To all whom it may concern:

Be it known that I, JOSEPH M. DUCLOS, of the city, county, and State of New York, have invented a new and useful Improvement in Iron Buildings, of which the following is a specification:

Figure 1 is an interior elevation, Fig. 2 an exterior elevation, Fig. 3 a horizontal section, and Fig. 4 a vertical transverse section, of my invention.

Similar of reference letters indicate corresponding parts.

This invention has for its object to simplify the construction of iron buildings by dispensing with the "backing up" or covering of the walls on the inner sides thereof. The invention consists in finishing the cast-metal walls of such structures on both sides with panels, ornaments, or otherwise, and in thereby making the inner backing up, by means of plaster or other devices, entirely unnecessary. The cost of putting up iron buildings is thus greatly reduced.

A in the drawing represents part of the wall of an iron building. This wall is a cast-iron plate faced and paneled on both sides, or otherwise ornamented or prepared on both sides to present finished surfaces. The plate A is made to overlap the faces of the cast or wrought iron columns or posts B B, which are recessed at the corners to receive the plates, as shown in Fig. 3. Angle-irons C C are placed against the posts and plates A in the manner shown in Fig. 3, and are secured thereto by bolts or rivets a a to constitute reliable connections and conceal the joint between A and B.

Having thus described my invention, I claim as new and desire to secure by Letters Patent—

The cast-iron building-plate A finished or paneled on both sides, substantially as and for the purpose herein shown and described.

JOSEPH M. DUCLOS.
